CLAIM

The ornamental design for a head strap set, as shown and described.

DESCRIPTION

FIG. 1 is a perspective view of a first pad set and a head strap body of a head strap set showing my new design where the first pad set is assembled with the head strap body;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the first pad set and the head strap body where the first pad set and the head strap body are assembled with VR glasses;

FIG. 10 is an exploded perspective view thereof;

FIG. 11 is a perspective view of a second pad set of the head strap set shown separately for ease of illustration;

FIG. 12 is another perspective view thereof;

FIG. 13 is a front elevational view thereof;

FIG. 14 is a rear elevational view thereof;

FIG. 15 is a left side elevational view thereof;

FIG. 16 is a right side elevational view thereof;

FIG. 17 is a top plan view thereof;

FIG. 18 is a bottom plan view thereof; and,

FIG. 19 is a perspective view of the second pad set and the head strap body where the second pad set and the head strap body are assembled with the VR glasses.

The broken lines in FIGS. 9, 10, and 19 showing the VR glasses depict environment and form no part of the claimed design. The other broken lines in the drawings depict portions of the head strap that form no part of the claimed design.
